UNITED STATES PATENT OFFICE.

CARL EDWARD WALDECK, OF WAYNE, NEW JERSEY, ASSIGNOR TO
HILLIARY ELDRIDGE AND JAMES C. YOUNG, OF JERSEY CITY,
NEW JERSEY.

DESIGN FOR A GLOBE-SUPPORT.

No. 88,073.

Specification for Design.

Patented June 12, 1906.

Application filed April 23, 1906. Serial No. 313,359. Term of patent 7 years.

To all whom it may concern:

Be it known that I, CARL EDWARD WALDECK, a citizen of the United States, and a resident of Wayne, in the county of Passaic and State of New Jersey, have invented a new, original, and ornamental Design for Globe-Supports, of which the following is a specification, reference being had to the accompanying drawings, forming part thereof.

Figure 1 is a side elevation; Fig. 2, a top plan view.

I claim—

The ornamental design for a globe-support, as shown.

CARL EDWARD WALDECK.
